UNITED STATES PATENT OFFICE.

JOSEPH S. DUNCAN, OF CHICAGO, ILLINOIS.

INDEX-TAB.

1,390,026.

Specification of Letters Patent.

Patented Sept. 6, 1921.

Application filed February 3, 1921. Serial No. 442,152.

To all whom it may concern:

Be it known that I, JOSEPH S. DUNCAN, a citizen of the United States, residing at Chicago, in the county of Cook and State of Illinois, have invented certain new and useful Improvements in Index-Tabs, of which the following is a specification.

The object of this invention is to provide a simple and novel index tab adapted to be 10 detachably engaged with cards of a card index system for classification purposes and which is provided with adjustable means whereby the cards may be subclassified from time to time without affecting the 15 main classification.

In other words, it is my object to provide an index tab of simple construction which can be easily applied to and detached from a card index card and which can be adjusted without being removed from the card 20 to indicate certain additional information and to perform certain additional functions.

I employ the term "card" in its broad generic sense as comprising a common card, 25 a printing device, or any other device which is capable of use in accordance with the ordinary card index system and to which my invention may be applied.

In the accompanying drawings I have 30 selected for illustrating the invention a card in the form of a printing device of a type used in the "Addressograph machine" and comprising a frame having printing plates detachably mounted thereon and adapted 35 to receive a reference card bearing any information relating to the address or other matter appearing in type characters on the plates.

Referring to the drawings—

Figure 1 is a front view of a printing device having my invention applied thereto.

Fig. 2 is a rear view of the printing device.

Figs. 3 and 4 show the tab with the movable member in two positions.

Fig. 5 is a detailed sectional view on the line 5, 5 of Fig. 3.

Referring to the drawings, the printing device comprises printing plates 6, 6 which 50 are removably secured in the frame 7. An information card (not shown) may be secured in the upper part of the frame by the bead 8 and the retaining lips 9. This frame is also provided with a plurality of alined 55 keepers 10 and 11 on the front and on the

back respectively of the frame and adapted to receive the stems 12 of the index tab substantially as shown in my Patent No. 1,026,253 patented May 14, 1912.

The index tab preferably comprises a pair 60 of stems 12 carried by and forming a part of the fixed member 13 which is provided with recesses or notches 14. A movable member 15 is pivotally mounted at 16 on the relatively fixed member 13 and this movable 65 member comprises two arms 17, 18 which are angularly disposed relative to each other. Each arm has a projection 19, 19' formed by indenting the member or otherwise to frictionally engage the relatively fixed member 70 13 when the movable member is swung on its pivot and also to hold the movable member in adjusted position. Thus, in the position shown in Fig. 3 the arm 17 of the movable member is in elevated position, and 75 it is so held by the projection 19' which engages the upper edge of the fixed member and by the projection 19 which engages a recess in the fixed member; and in the position shown in Fig. 4 the arm 18 of the movable member is elevated and is so held by 80 the projection 19 which engages the upper edge of the fixed member, and by the projection 19' which engages a recess 14 in the fixed member. The movable member operates 85 close to the fixed member and the projections will operatively engage the fixed member sufficient to prevent accidental dislodgment of the movable member from adjusted position but at the same time will 90 permit adjustment of the movable member with very little effort.

I prefer to provide a shoulder 20 at the juncture of each stem with the main portion of the fixed member by offsetting the 95 stems so that they will lie in a different plane than that of the main portion of the fixed member, but preferably parallel therewith. When the tab is arranged in the frame as shown in Figs. 1 and 2 the offset 100 stems cause the main portion of the fixed member to be spaced sufficiently from the frame to permit the movable member to be easily adjusted from one position to another. The stems are provided with openings 21 at their extremities to engage protuberances on the frame for retaining the tabs in place.

The recesses 14 are located in the arc of travel of the projections 19, 19' during the 110

adjustment of the movable member and when a projection is engaged with a recess it tends to restrain the member from swinging movement in either direction because 5 the projection will engage an edge of the recess in its arc of travel at the bottom as well as at the top thereof. My invention may be embodied in a tab with one stem as well as in a tab with two stems as shown 10 and various other changes in the form, proportion and construction of parts may be made within the scope of the appended claims without departing from the spirit or sacrificing the advantages of the invention. 15 My improved tab can be used in many different ways for many different purposes. By coloring the movable member or affixing colored markers thereto the possibilities of classification may be greatly extended. I 20 may illustrate one practical use of the invention as follows:

In the credit department of large retail stores a card index of credit customers is maintained. When bills are rendered to the 25 customers the index tabs are mounted on the frames to indicate when these bills were mailed. When customers pay their bills within a certain time the movable member of the index tabs on their cards may be 30 left in neutral position as shown in Figs. 1 and 2; but after a certain time the movable members of the index tabs of all customers whose bills have not been paid may be 35 swung to the position shown in Fig. 3 and maintained in this position until the bills are paid, whereupon the movable members will be swung to neutral position. If the time comes when further credit is discontinued the movable members may be 40 moved to the position indicated in Fig. 4. The movable members may be moved to the position of Fig. 3 when the bills are rendered, to neutral position of Figs. 1 and 2 when bills are paid and to the position of 45 Fig. 4 to indicate that payment is over due, that statements have been rendered, further credit refused or something else. I know that the tab can be used in many different ways but I consider the foregoing will sufficiently indicate the general use and advantages of my invention.

It will be understood of course that the movable member of the tab may be employed to operate the selector mechanism of 55 a printing machine so that a tray or drawer containing these cards may be deposited in an addressing machine and run through the machine one at a time to address statements or envelopes or other matter with the addresses on those cards in which the arm 17 is elevated, or those on which the arm 18 is elevated, or those on which the movable member is in neutral position as may be required.

65 Thus my invention may be used like the

adjustable indicator 10 of U. S. Patent No. 1,161,045 patented November 23, 1915, and for the purposes therein described.

I claim:

1. An index tab comprising a member 70 adapted to be fixedly engaged with a card of an index system, and a movable member pivotally mounted on said fixed member and means to hold said movable member in a plurality of positions.

2. An index tab comprising a member adapted to be fixedly engaged with a card of an index system, and a movable member pivotally mounted on one side of said fixed member, one of said members having projections to frictionally engage the other member in the swinging movement of said pivoted member.

3. An index tab comprising a member 85 adapted to be fixedly engaged with a card of an index system, and a movable member pivotally mounted on one side of said fixed member, said fixed member having recesses and said movable member having lateral projections to engage said recesses in different 90 adjustments of said movable member.

4. An index tab comprising a member adapted to be fixedly engaged with a card of an index system, and a movable member pivotally mounted on one side of said fixed member and having oppositely disposed arms, said fixed member having recesses on opposite sides of said pivot and said movable member having lateral projections in operative relation to said recesses so that 95 when one arm is lifted the other arm will have its projection engaged with the adjacent recess.

5. An index tab comprising a member 105 adapted to be fixedly engaged with a card of an index system, and a movable member pivotally mounted on one side of said fixed member and having angularly disposed arms, said fixed member having recesses on opposite sides of said pivot and said movable member having lateral projections disposed in operative relation to said recesses and so that when one arm is lifted its projection will engage the top edge of the fixed member and the projection on the other arm 110 will engage its recess.

6. The combination of an index card having tab retaining means, of a tab comprising a member adapted to be fixedly engaged with said retaining means, and a movable member pivotally mounted on one side of said fixed member between the fixed member and the card, and said fixed member being spaced from the card to permit the operation of the movable member between the 125 fixed member and the card.

7. The combination of an index card having tab retaining means, of an index tab comprising a member adapted to be fixedly engaged with said retaining means and hav-

ing that portion thereof above the retaining means located partly behind and offset from the card, and a movable member pivotally mounted on said fixed member to swing between said fixed member and the card and having angularly disposed arms, and means on said tab for limiting the swinging movement of the movable member.

8. The combination of a card of an index system, a tab comprising a member adapted to be fixed to the said card, a movable member pivoted to said fixed member, and means to secure said movable member in a plurality of positions relative to said fixed member.

JOSEPH S. DUNCAN.
